(57) **CLAIM**

The ornamental design for a soap dispenser, as shown and described.

DESCRIPTION

FIG. 1 is a bottom perspective view of a soap dispenser showing my new design;

FIG. 2 is a top, perspective view thereof;

FIG. 3 is a rear perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof.

FIG. 10 is an enlarged detailed view of the encircled area labeled **10** in FIG. 1;

FIG. 11 is an enlarged detailed view of the encircled area labeled **11** in FIG. 2; and,

FIG. 12 is an enlarged detailed view of the encircled area labeled **12** in FIG. 2.

The broken lines in the figures are for the purposes of illustrating portions of the soap dispenser, that form no part of the claimed design.
